UNITED STATES PATENT OFFICE.

JAMES H. BROWN, OF PARIS, ILLINOIS.

DESIGN FOR A COVER FOR VESSELS.

SPECIFICATION forming part of Design No. 30,762, dated May 16, 1899.

Application filed April 19, 1899. Serial No. 713,670. Term of patent 7 years.

To all whom it may concern:

Be it known that I, JAMES H. BROWN, a citizen of the United States, residing at Paris, in the county of Edgar and State of Illinois, have **5** invented and produced a certain new and original Design for Covers for Vessels; and I do declare the following to be a full, clear, and exact description of the invention, such as will enable others skilled in the art to which it **10** pertains to make and use the same.

The invention has relation to a new and original design for covers for vessels; and it consists of a design of the configuration shown in the accompanying drawings, in which—

15 Figure 1 is a perspective view of my invention, and Fig. 2 is a longitudinal sectional view.

The leading feature of my design comprises the body portion 1, having concentric corrugations 2 and a central cylindrical extension **20** 3, the sides of which are perforated and the top of which is flat and imperforate.

What I claim is—

The design for a cover for vessels, as herein shown and described.

25 In testimony whereof I have hereunto set my hand in presence of two subscribing witnesses.

JAMES H. BROWN.
